CLAIM

The ornamental design for a garment pocket as shown and described.

DESCRIPTION

FIG. 1 is a first perspective view of a front left side of a garment pocket showing my new design;

FIG. 2 is a second perspective view of a front right side thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The smaller broken lines shown in the drawings illustrate portions of the article and form no part of the claimed design. The larger broken lines showing the wearer in FIGS. 1-2 depict environment and form no part of the claimed design.

1 Claim, 5 Drawing Sheets
